UNITED STATES PATENT OFFICE.

GEORGE G. SCHROEDER, OF WASHINGTON, DISTRICT OF COLUMBIA,
ASSIGNOR TO INDUSTRIAL TRANSPORTATION COMPANY, A COR-
PORATION OF THE DISTRICT OF COLUMBIA.

AERIAL ELECTRIC TRANSPORTATION SYSTEM.

No. 826,367.

Specification of Letters Patent.

Patented July 17, 1906.

Application filed November 14, 1904. Serial No. 232,637.

To all whom it may concern:

Be it known that I, GEORGE G. SCHROEDER, a citizen of the United States, residing at Washington, in the District of Columbia, have invented new and useful Improvements in Aerial Electric Transportation Systems, of which the following is a specification.

This invention has relation to aerial electric transportation systems; and it consists 10 in the novel construction and arrangement of its parts, as hereinafter shown and described.

The object of the invention is to provide such a system having a car or carrier which 15 is adapted to travel upon a suspended cable or track. Said car or carrier is fitted with an electric motor which constitutes a prime mover and furnishes the motive power. Suspended, preferably, above and extending 20 parallel with each other are four current-wires, two of them adapted to act for transmitting the current to the motor and two of them adapted to act as return-wires. The motor is provided with four trolley-arms, 25 each of which is adapted to come in contact with one of the said current-wires, and each of the said trolley-arms is electrically connected with the said motor.

The prime object of the system is to so arrange 30 the apparatus that the car may be sent back and forth upon the cable, stopped at any desired point, and made to travel at any desired rate of speed. The movement of the car in either direction is controlled by the manipulation of switches and a pole-changer 35 located at either terminal station or a way station. Each car or motor is provided with a means to prevent rocking thereof in the line of travel and also to guide the car around 40 curves. Said means also prevents any tendency of the motor to climb or jump the track. The trolley-arms are also arranged so as to prevent lateral rocking of the car. Said trolley-arms are preferably mounted 45 upon a base which is pivoted to the top of the frame of the motor, so that the said trolley-arms may follow the wires while the motor is rounding a curve in the track.

Other objects and special constructions 50 are presented, which will be pointed out in the following description and covered in the subjoined claims.

This system is especially adapted for use

in logging-camps and at mills for bringing in logs from a distance and dropping them at 55 any desired point, also for removing sawed lumber and slabs and other waste from the mill. It may also be used for transporting merchandise and for moving earth, &c., from excavations. In fact, its uses are too numerous to specify, as it may be used to advantage in all instances where transportation is necessary.

In the accompanying drawings, Figure 1 is a perspective view of the carrier mounted 65 upon the suspended track. Fig. 2 is a diagrammatic view showing the current-wire and the mechanism for controlling the same. Fig. 3 is a side elevation of a car or carrier located upon the track. Fig. 4 is an end elevation of the car or carrier located upon the track. Fig. 5 is a side elevation of the motor used in the car or carrier with parts removed. Fig. 6 is an edge elevation, partly 70 in section, of a device used to prevent rocking of the motor in the line of travel and for the purpose of guiding the same around the curves. Fig. 7 is a transverse sectional view of the motor. Fig. 8 is a horizontal sectional view of the disk for transmitting the current 75 to the motor; and Fig. 9 is a side elevation, partly in section, of the trolley-arms and their support.

The system consists of the suspended cable or track 1, above which is located the 80 wires 2 2 and 3 3. All of the said wires are parallel to each other and parallel to said track. The electric generator 4 is located at any suitable point. The wire 5 connects one pole thereof with the switch-socket 6. The 85 wire 7 connects the opposite pole of the said generator with the switch-socket 8. The fuses 9 9 are located at suitable points on the wires 5 and 7. The switch 10 is adapted to enter the sockets 6 and 8, and the wire 11 90 connects one of the ends of said switch with the socket 12, and the wire 13 connects the other end of the switch 10 with the socket 14. The wire 15 connects the wire 11 with one of the line-wires 2. The wire 16 connects the 95 wire 13 with the other line-wire 2. The said line-wires 2 2 are connected through the trolley-arms of the carrier with the field 17 of the motor 18. The cross-wire 19 connects the socket 12 with the socket 20, and the cross-wire 21 connects the socket 14 with the 100 105

socket 22. The pole-changer 23 (shown in Fig. 1 in the form of a switch) is adapted to be swung into either the sockets 12 and 14 or 20 and 22. One end of the switch constituting the pole-changer 23 is connected, by means of the wire 24, with one of the line-wires 3, and the opposite end of the said switch 23 is connected, by means of the wire 25, with the other line-wire 3. The rheostat 26 is located, preferably, upon the wire 25. Both of the line-wires 3 are electrically connected, by means of the trolley-arms of the carrier, with the armature 27 of the motor 18. The armature 27 is held in a fixed position against rotation, as will be hereinafter explained, while the field 17 rotates about the said armature.

Presuming that the parts are in the positions as indicated in Fig. 2, the current starts from the generator 4, passes along the wire 5 to the socket 6, then through the switch 10 along the wire 11, then along wire 15 to the inner line-wire 2, thence through the armature 17 along the outer line-wire 2, thence along wire 16 to the wire 13, then through switch 10 along wire 7 back to the opposite pole of the generator 4. At the same time the current passes from wire 13, through socket 12 and along wire 19, to socket 20, thence along one end of the switch 23 to wire 25, thence along the said wire 25, through rheostat 26, to the inner line-wire 3, thence to the armature 27, thence along the outer line-wire 3, thence along wire 24 to the other end of the switch, thence to socket 22, thence along the cross-wire 21 to socket 14, thence back to the generator over the wire 13 and its connections. By supplying the current to the armature and the field as above described the said armature is rotated in one direction. To change the direction of rotation of the armature, the switch 23 is disengaged from the sockets 20 and 22 and turned into the sockets 12 and 14. The current then passes from the generator 4 to the field 17, as above described. While the course of the current through the armature 27 is reversed—that is, the current passes from the socket 12 along one end of the switch 23, then along wire 24 to the outer line-wire 3, thence through the armature 27, thence back along the inner line-wire 3, thence along wire 25, through the rheostat 26, to the opposite end of the switch 23, thence along said switch to the socket 14, thence along the wire 13 and its connections back to the generator 4. Thus the rotation of the field 17 about the armature 27 is reversed. To cut off the current at any desired point, the switch 10 is disconnected from the sockets 6 and 8, and thus the motor is stopped. The switches 10 and 23 may be included in one instrument, as may also the rheostat 26, such an instrument being commonly known as a "starting-box." At any event the switches 10 and 23

and the rheostat 26 should be located near each other, so as to be operated by one person.

The motor 18 consists of an outer shell or casing, within which the armature 27 and the field 17 is housed. Around the periphery of the said casing extends a grooved annulus 28, which is adapted to run upon the cable 1. The disk 29 is so located as to rotate with the casing of the motor 18. The outer face of the said disk is provided with metal rings 30, 31, 32, and 33. The outer ring 30 is connected, by means of the wire 34, with one of the brushes 35 of the armature, and the ring 31 is connected, by means of the wire 36, with the other brush of the said armature. The ring 32 is connected, by means of the wire 37, with one of the fields 17 of the motor, the wire 38 connecting the fields together and the wire 39 connecting one of the said fields with the ring 33. Thus the electrical connections through the motor 18 are completed. The trolley-arms 40 are each provided at their upper ends with a trolley-wheel 41, and the wires 42 extend down from the said trolley-wheels and are connected with the brushes or carbons 43, the inner ends of which bear against the rings 30, 31, 32, and 33. The lower ends of the trolley-arms 40 are pivoted to the cross-piece 44. The said trolley-arms at their pivotal points are in alignment with each other; but two of the said trolley-arms extend in one direction and bear against the inner line-wires 2 and 3, and the two remaining trolley-arms extend back in substantially an opposite direction and bear against the outer line-wires 2 and 3. The cross-piece 44 is pivoted at its middle t the upper portion of the frame 45, the pivot-bolt 46 having a vertical opening through which the wires 42 pass. The frame 45 is provided with a forwardly and rearwardly extending portion 47, at the lower ends of which are secured the vertical extending shafts 48. The guide-wheels 49 are journaled at the lower ends of the shaft 48 and are adapted to run upon the cable 1. The coil-springs 50 are interposed between the lower ends of the portions 47 and a suitable collar on the shaft 48 just above the wheels 49, the tension of said coil-springs being to force the wheels 49 away from the lower ends of the portions 47. The side portions 51 and 52 extend down from the top 45, the portion 51 being secured at its lower end to one end of the shaft of the motor 18, while the portion 52 extends down on the opposite side of the motor 18 and is connected to the opposite end of the shaft thereof and extends down, forming the shank 53, to which the load 54 may be attached.

It will thus be seen that as the carrier moves back and forth the wheels 49 and their connections will have a tendency to prevent rocking of the motor in the line of travel. The said wheels will also guide the motor in

going around curves and have a tendency to prevent any inclination on the part of the motor from riding up above the cable 1. The swivel connection between the cross-piece supporting the lower ends of the trolley-arms 40 and the top-piece 45 of the frame will compensate for any change in direction which might occur between the current-wires notwithstanding any such lack of alinement, the trolley-arms 40 being pivoted in alinement at their lower ends to the cross-piece 44 and extending up and in front and behind a perpendicular erected from the center of the motor 18, having a tendency to prevent any lateral rocking of the motor or the load carried by the same.

Having described my invention, what I claim as new, and desire to secure by Letters Patent, is—

1. In a system such as described, an elevated track adapted to support a carrier, current-wires located above said track, trolley-arms pivoted at their lower ends to said carrier, some of said trolley-arms extending in front of and the remainder extending back of a perpendicular erected through the center of said carrier, each of the said trolley-arms engaging one of the said current-wires.

2. In a system such as described, an elevated track, a carrier adapted to travel upon said track, current-wires located above said track, a plurality of trolley-arms pivoted at their lower ends in transverse alinement to said carrier, and adapted to engage said current-wires.

3. In a system such as described, an elevated track, a carrier adapted to travel upon said track, current-wires located above said track, trolley-arms pivoted at their lower ends in transverse alinement to each other to a cross-piece, said cross-piece being swiveled to said carrier.

4. In a system such as described, an elevated track, a plurality of current-wires located above said track and extending parallel with the same, and at the same level with each other, trolley-arms pivoted in alinement with each other at their lower ends to said carrier, and extending up and engaging said current-wires, some of said trolley-arms extending in front of and the remainder extending back of a perpendicular erected through the center of said carrier.

5. In a system such as described, an elevated track, a carrier adapted to travel upon said track, current-wires located above said track, the frame of said carrier having forwardly and rearwardly extending portions, wheels carried by said portions and adapted to run upon said track.

6. In a system such as described, an elevated track, current-wires located above said track, a carrier adapted to travel upon said track and having trolley-arms to engage said current-wires, the frame of said carrier having forwardly and rearwardly extending portions, wheels carried by said portions and adapted to run upon said track, a means for permitting said wheels to move vertically, said means being provided with springs to maintain the said wheels in engagement with track.

7. In a system such as described, a track, current-wires extending parallel to said track, a carrier adapted to travel upon said track, a cross-piece swiveled to said carrier, trolley-arms pivoted in transverse alinement at their lower ends to said cross-piece, and adapted to engage said current-wires.

8. In a system such as described, a track, a carrier adapted to travel upon said track, current-wires extending parallel with said track, a cross-piece swiveled to said carrier, trolley-arms pivoted to said cross-piece at their lower ends in transverse alinement, current-wires leading from said trolley-arms to the carrier and passing through the swiveled connection between the cross-piece and the carrier.

9. In a system such as described, a track, current-wires extending parallel to said track, a carrier adapted to travel upon said track, and having trolley-arms adapted to engage said current-wires, a motor located upon said carrier, and having a non-rotatable armature with a rotatable field, a disk rotating with said field, and having rings which are electrically connected with the field and the armature, current-wires leading from the trolley-arms and being connected to brushes which engage the rings of said disk.

10. In a system such as described, a track, current-wires extending parallel with said track, a carrier adapted to travel upon said track, and having trolleys which engage said current-wires, a motor located upon said carrier and having a non-rotatable armature and a rotatable field, a disk rotating with said field, and having on its outer face rings which are electrically connected with the armature and field, brushes arranged opposite to and engaging each of said rings, and electric wires extending from the trolley-arms and connected with each of said brushes.

In testimony whereof I affix my signature in presence of two subscribing witnesses.

GEORGE G. SCHROEDER.
